CLAIM

The ornamental design for a toy vehicle track coupler, as shown and described.

DESCRIPTION

FIG. 1 is a perspective view of a toy vehicle track coupler according to the present invention;

FIG. 2 is a top view of the toy vehicle track coupler of FIG. 1;

FIG. 3 is a bottom view of the toy vehicle track coupler of FIG. 1;

FIG. 4 is a left side view of the toy vehicle track coupler of FIG. 1;

FIG. 5 is a right side view of the toy vehicle track coupler of FIG. 1;

FIG. 6 is a front view of the toy vehicle track coupler of FIG. 1; and,

FIG. 7 is a rear view of the toy vehicle track coupler of FIG. 1.

The broken lines shown in the figures are included for the purpose of illustrating the unclaimed portions of the article and form no part of the claimed design.

1 Claim, 3 Drawing Sheets
